DESIGN FOR A LACE

Ralph L. Anderson, New York, N. Y.

Application September 12, 1947, Serial No. 141,359

Term of patent 3½ years

(Cl. D47—6)

To all whom it may concern:

Be it known that I, Ralph L. Anderson, a citizen of the United States, residing at New York, in the county of New York and State of New York, have invented a new, original, and ornamental Design for a Lace, of which the following a specification, reference being had to the accompanying drawing, forming a part thereof.

In the drawing the figure is a plan view of a lace, showing my new design.

A complete design unit is shown. This design unit is repeated in the vertical and horizontal directions.

I claim:

The ornamental design for a lace, as shown and described.

RALPH L. ANDERSON.
